Attorney

UNITED STATES PATENT OFFICE.

MICHAEL J. SKORTZ, OF CLEVELAND, OHIO.

TOILET FLUSHER.

Application filed March 29, 1923. Serial No. 628,571.

To all whom it may concern:

Be it known that I, MICHAEL J. SKORTZ, a citizen of the United States, residing at Cleveland, in the county of Cuyahoga and State of Ohio, have invented certain new and useful Improvements in a Toilet Flusher, of which the following is a specification.

The present invention relates to toilet flushers and has for its principal object to generally improve upon devices of this nature by providing a simple and efficient structure, one which will be reliable in operation, durable, inexpensive to manufacture, and well adapted to the purpose for which it is designed.

Another important object of the invention is to provide a flusher of this nature with means for retarding the closing of the flusher so that a desired amount of water may pass therethrough.

With the above and numerous other objects in view as will appear as the description progresses, the invention resides in certain novel features of construction, and the combination and arrangement of parts as will be hereinafter more fully described and claimed.

In the drawing—

30 The figure is a vertical section through the flusher portions being shown in elevation.

Referring to the drawing in detail it will be seen that the casing A is formed in two sections 1 and 2. The section 1 is open at its upper end and provided with an annular flange 2' while its bottom end is provided with a cylinder 3 that projects slightly into the section 1. An inlet nipple 4 is communicated with the section 1 and preferably formed integral therewith as is indicated in the drawing. Section 2 of the device is provided with a frusto-conical portion 5 which forms a valve seat. The portion above this valve seat is smaller in diameter than the portion therebelow and an outlet nipple 6 communicates with the upper or smaller portion. A reduced threaded extension 7 is situated on the upper end of the section 2 and has disposed therein packing 8 which is held in place by the gland 9. A cap 10 is provided with a threaded portion for engagement with the extension 7 and is provided with a reduced bore adjacent its threaded portion so as to form the shoulder 11 which bears against

the gland 9 and holds the packing 8 in place.

A valve stem 12 is disposed longitudinally of the casing A extending also through and beyond the cap 10. The lower portion of this stem 12 is threaded and a valve 13 is mounted on the threaded portion being held in place by the jam nuts 14 so that its relative position on the rod may be adjusted. This valve 13 is adapted to seat upon the valve seat formed by the frusto-conical portion 5. A plunger 16 is mounted on the lower end of the rod being engaged with the threaded portion thereof and a set screw 29 is mounted underneath the plunger. This plunger is adapted to reciprocate in the cylinder 3 and is provided with a crevice or channel 17. A compressible coil spring 18 is disposed about the stem 12 and rests upon the gland 9. The upper end of this spring is engaged by a sleeve 20 threaded on the upper end of the stem 12 and movable through the cap 10. A suitable knob or handle 21 is mounted on this same end of the stem 12 on top of the sleeve 20 and a set screw 23 is threaded in the end thereof for engagement with the end of the stem. When it is desired to operate the flusher the stem is depressed by engagement with the knob 21 thereby releasing the valve 13 from its seat so that the water may flow through the casing A entering through the nipple 4 and departing through the nipple 6. The pressure of the water will have a tendency to close the valve and to prevent the valve from closing too quickly I have provided the aforementioned plunger which will greatly retard the closing of the valve and in fact will retard it for a sufficient length of time so that ample water may pass through the casing A. It is preferable that the plunger 16 have the crevice 17 in order that the movement of the valve will not be too greatly retarded. The spring 18 with the aid of the water pressure tends to close the valve and retains it closed when the device is not being used. The tension of this spring may be varied by longitudinal movement of sleeve 20 and thus the speed with which the valve 13 on the stem 12 may close can be regulated. The device is easily assembled and the sections 1 and 2 may be easily disengaged from and assembled with each other it being noted that section 2 is provided with a flange 25 adapted to be fixed to the flange 2' by screws 26 and I

prefer that a gasket 27 be disposed between these flanges 2' and 25. The nipple 4 is constructed with a threaded wall flange 28.

Although I have described my invention with a degree of particularity it is to be understood that numerous changes in the details of construction and in the combination and arrangement of parts may be resorted to without departing from the spirit of the invention as hereinafter claimed.

Having thus described my invention what I claim as new is:—

In a flusher of the class described, a casing provided with a valve seat, a valve associated with the valve seat, a reduced externally threaded extension on the casing, a valve stem attached to the valve and extending through the extension of the casing and therebeyond, said extension provided with an internal shoulder, packing on said shoulder about said valve stem, a gland disposed on said packing about said valve stem

and provided with a flange resting on the upper end of said extension, a cap having an internally threaded portion for receiving the extension of the casing and provided with a reduced bore extending longitudinally from the internally threaded portion so as to form a shoulder adapted to engage the gland and hold it and the packing in place, said stem extending through the reduced bore of the cap, a spring disposed about said stem and resting on the gland, and a sleeve threaded on the stem for tensioning the spring, the outer end of said sleeve being in the form of a knob and a set screw threaded through the knob in the sleeve to engage the end of the stem.

In testimony whereof I affix my signature in presence of two witnesses.

MICHAEL J. SKORTZ.
